J. W. McCONNON

CONTAINER FOR LIQUIDS

Filed Sept. 9, 1926

UNITED STATES PATENT OFFICE.

JOHN WALTER McCONNON, OF PALMERSTON NORTH, WELLINGTON, NEW ZEALAND.

CONTAINER FOR LIQUIDS.

Application filed September 9, 1926, Serial No. 134,522, and in New Zealand August 10, 1926.

This invention relates to containers for holding liquid, and is directed particularly to containers adapted for holding liquid fuels, illuminating oils and the like.

Heretofore, liquid fuels and illuminating oils, have been either conveyed in bulk or in drums or tins, and in the latter case, the tins are discarded after being emptied. The value of the tins discarded is considerable.

When drums are used considerable space in stowage aboard ship, and elsewhere is wasted, owing to the shape of the drums, and the return freight on empty drums is as much as the outward freight on full drums, moreover the drums only last a few trips and are discarded thereby entailing further loss.

The present invention has for its object the provision of means whereby a tin receptacle of comparatively large dimensions may be used for conveying a large bulk of liquid without fear of damage to the receptacle and so as to result in a considerable saving of tin for a given quantity of liquid, the shape of the container being such, that little or no space is lost, in stowing numbers thereof.

A further provision of the invention is to make the container collapsible so that after it has been emptied, it can be taken to pieces, packed into a small space and be returned to the place whence it came, and used repeatedly. Being collapsible, the containers may be returned as deck cargo, or stowed elsewhere on board ship, as is most convenient and economical.

The container provided by this invention comprises a receptacle in which the liquid is placed, and a protective casing in sections adapted to be secured around said receptacle.

The protective casing is strengthened and the sections thereof secured together by means of external ribs, preferably horizontal and vertical angle iron ribs secured to the sections so as to project beyond the latter, the ribs of each section overlapping the ribs of other sections, whereby said sections may be secured together by fastenings passed through the overlapping ribs at the corners of the container.

The casing is lined with felt, and the top, the bottom and the ends thereof are flanged, the top and the bottom to embrace the sides

and ends and the latter to embrace the sides channels being also provided on said sides to receive the flanges of the top and the bottom.

When the casing is taken to pieces, the top and the bottom are capable of being secured together to provide a container for the ends and sides, some of the ribs on said ends and sides being detachable therefrom in order to facilitate packing of the sections.

The invention will be further described, with the aid of the accompanying drawing wherein:

Figure 1 is a side elevation.

Figure 2 a plan view and

Figure 3 an end view of the improved container while,

Figure 4 is a part sectional view of a side and top, illustrating a detail of construction and

Figure 5 is a longitudinal section of the casing, dismantled and packed to save space, when not being used.

The protective casing comprises sides 1, ends 2, top 3 and bottom 4, all made of sheet steel or sheet iron, and formed so that the casing when assembled will have all right angle corners, whereby numbers of containers may be stowed together without loss of space.

The sides, ends, top and bottom, are all lined with felt 5, to serve as padding to a sealed receptacle 6 (Figure 4) destined to hold the liquid to be transported, and which the protective casing is made to enclose.

The top 3 and bottom 4 are flanged all round as at 3^a and 4^a respectively, the top being strengthened by a longitudinal angle iron 7 either bolted or welded thereto, and having cross angle irons 8 bolted to the angle iron 7, while the bottom 4 is strengthened by a longitudinal angle iron 9 either bolted or welded thereto and has cross angle irons 10, bolted to the angle iron 9.

The sides 1 have vertical angle irons 11, either bolted or welded thereto to strengthen same with horizontal angle irons 12 bolted to said angle irons 11, while the ends 2 have vertical angle irons 13 either bolted or welded thereto, and horizontal angle irons 14 bolted to said angle irons 13.

All of the angle irons project beyond the edges of the top, bottom, sides and ends.

The ends 2 are formed with flanges 2^a to embrace the ends of the sides 1, while the flanges 3^a, and 4^a, of the top 3 and bottom 4 are provided to embrace the upper and lower edges of the sides 1 and ends 2.

Channels 15 formed by securing Z irons to the upper and lower edges of the sides 1 and ends 2 are provided to receive the flanges 3^a and 4^a, of the top 3 and bottom 4.

10 The upper and lower ends of the vertical angle irons 11 and 13 of the sides 1 and ends 2 respectively, are set out from said sides and ends to permit the flanges 3^a and 4^a of the top and bottom to pass between said angle irons and the sides and ends and into the channels 15.

15 In assembling the casing around a liquid filled receptacle 6, the vertical angle irons 11 of the sides 1, are bolted to the cross angle irons 8 and 10 of the top 3 and bottom 4, the horizontal angle irons 12 of said sides being bolted to the horizontal angle irons 14 of the ends 2, while the vertical angle irons of the latter are bolted to the longitudinal angle irons 7 and 9 of the top 3 and bottom 4, all of the joints just effected being made at corners of the container.

20 This securing of the sections of the casing together combined with the flanging of the top, bottom and ends, and the insertion of the flanges 3^a and 4^a in the channels 15, ensures a rigid and strong protective casing being provided for the liquid receptacle 6.

25 In order to pack the casing to economize space, as when same is being returned empty the casing is taken to pieces, and the angle irons 8, 10, 12 and 14 removed from the top 3, bottom 4, sides 1 and ends 2 respectively.

30 The sides 1, ends 2 and detached angle irons, are placed between the top and bottom 3 and 4, which are fitted flange to flange and secured together by lugs 16 on one of the flanges, being secured preferably by screwing to the other of said flanges.

35 45 An inlet and outlet provided with a screw cap 18 enables liquid to be placed within and emptied from the container to which a vent 19 provided with a screw cap is also fitted.

40 50 Although the protective casing described herein is applied to liquid receptacles, it is quite obvious that said casing can be used with or without an inner receptacle for the carriage of the goods without departing 55 from the spirit of the invention.

What I do claim and desire to obtain by

Letters Patent of the United States of America is:—

1. A container comprising a receptacle of relatively fragile material, a protective casing surrounding said receptacle and composed of sectional members arranged to cover the surfaces of the receptacle, a cushion lining on the inner face of said sections, and reinforcing ribs on the outer surface of said sections extending at an angle to the edges of each section and projecting beyond said edges, the projected end of said ribs of adjacent sections being detachably secured together. 70

2. A container comprising a casing having top, bottom, sides and end walls, the end walls being flanged to embrace the adjacent edges of the side walls, the top and bottom walls being flanged to embrace adjacent 75 edges of the end and side walls, channels on the end and side walls to receive the flanges of said top and bottom walls, reinforced ribs on the outer face of said walls and projecting beyond the edges of said walls, corresponding ends of the ribs of adjacent walls being arranged to lie in close position when the parts are assembled, and means for detachably securing said adjacent ends of said ribs together. 80

3. A container comprising a casing having top, bottom, side and end walls, the end walls being flanged to embrace the adjacent edges of the side walls, the top and bottom walls being flanged to embrace adjacent 90 edges of the end and side walls, channels on the end and side walls to receive the flanges of said top and bottom walls, reinforcing ribs on the outer face of said walls and projecting beyond the edges of said walls, corresponding ends of the ribs of adjacent walls being arranged to lie in close position when the parts are assembled, means for detachably securing said adjacent ends of said ribs together, and certain of said ribs on the wall 95 sections being removable, whereby when the edges of the flange of the top and bottom walls are placed together a receptacle is provided for housing all of the remaining parts of the casing, when in knocked-down position, and means for securing the flanges of the bottom wall together for holding said parts in compact knocked-down relation. 100

In testimony whereof I have signed my name to this specification.

JOHN WALTER McCONNON.
